Primary Examiner — Paula Allen Greene(74) *Attorney, Agent, or Firm* — Georgi Korobanov(57) **CLAIM**

The ornamental design for wireless music headband, as shown and described.

DESCRIPTION

FIG. 1 is a perspective view of a wireless music headband showing my new design according to a first embodiment; FIG. 2 is a front view thereof;

FIG. 3 is a rear view thereof;

FIG. 4 is a right side view thereof;

FIG. 5 is a left side view thereof;

FIG. 6 is a bottom plan view thereof; and,

FIG. 7 is a top plan view thereof.

The broken lines depict portions of the wireless music headband and form no part of the claimed design.
